GAME APPARATUS

Harry E. Williams, Los Angeles, Calif., assignor, by mesne assignments, to Rock-Ola Manufacturing Corporation, Chicago, Ill., a corporation of Delaware

Application March 16, 1936, Serial No. 69,154

1 Claim. (Cl. 101—66)

This invention relates to game apparatus.

It is an object of this invention to provide an improved game apparatus which is relatively simple and inexpensive in construction and efficient in use.

Another object of the present invention is to provide a new and improved score-recording device which is particularly adapted for use in conjunction with amusement or game apparatus.

10 A further object of the present invention is to provide a new and improved score-recording device which is particularly adapted for use in conjunction with amusement or game apparatus of the so-called pin and marble game type.

15 Additional objects of the present invention are: to provide a novel auxiliary and coin-operated control device for the resetting mechanism for the printing drum and which control device is rendered effective to reset the printing drum when the ball-retaining member is being returned to initial position after operation thereof; to provide a main and non-coin-operated control device for the printing and web-severing mechanism; to construct the auxiliary control device for the printing and web-severing mechanism in such a manner that the same works in conjunction with the coin slide, when the latter is operated, to operate the printing and web-severing mechanism in the event that the player, for any reason, fails to operate the main and non-coin-operated control device for the printing and web-severing mechanism after completing a game; and to construct the web-advancing device in such a manner that the same is operated by the coin slide and associated mechanism only after the printing and web-severing operations have been effected by operation of the auxiliary control device for the printing and web-severing mechanism.

40 Other objects will appear hereinafter.

The invention consists in the novel combination and arrangement of parts to be hereinafter described and claimed.

45 The invention will be best understood by reference to the accompanying drawings showing the preferred form of construction, and in which:

Fig. 1 is a fragmentary top plan view, partly in section, of a preferred form of the present invention, showing the same arranged in the cabinet of an amusement game apparatus of the pin and marble game type;

Fig. 2 is a view on line 2—2 in Fig. 1, partly in side elevation and partly in section;

Fig. 3 is a view on line 3—3 in Fig. 1, partly in elevation and partly in section, showing

certain parts of the operating mechanism for the score-recording device;

Fig. 4 is a sectional view on line 4—4 in Fig. 1, showing certain parts of the score-recording device and the operating mechanism therefor;

Fig. 5 is a sectional detail view on line 5—5 in Fig. 1 showing the arrangement of the inking rollers relative to the printing drum;

Fig. 6 is a sectional view on line 6—6 in Fig. 1, showing the impression-transmitting and web-severing device and showing the main or non-coin-operated control device therefor;

Fig. 7 is a plan view, showing certain parts of the web-advancing device, and also showing certain parts of the auxiliary control device for the impression-transmitting and web-severing device;

Fig. 8 is a bottom plan view of a part of the web-advancing device shown in Fig. 7;

Fig. 9 is a schematic diagram of an electrical circuit embodied in the invention; and

Fig. 10 is a perspective detail view of the control switch for the resetting mechanism for the printing drum.

A preferred form of the present invention is shown in the drawings, is therein generally indicated at 10, and is shown arranged in the cabinet 11 of a so-called pin and marble game, said cabinet including an inclined playing board 12 which is provided with ball exit openings 13.

Slidably mounted in the cabinet 11, below the inclined playing board 12, is a ball-retaining member 14 which is provided with ball exit openings 15 and these exit openings 15 are normally disposed in registration with the ball exit openings 13. Likewise formed in the inclined playing board 12 is a ball-receiving pocket 93 (Fig. 2) and the lower end portion of the ball-retaining member 14 is adapted to temporarily retain or support balls in this pocket 93.

Arranged in each of the ball-receiving pockets or exit openings 15 is a resilient switch element 16 and this switch element 16 is engageable with a relatively stationary switch element 17, each pair of these switch elements 16 and 17 forming a switch 18. These switches 18 are arranged in an electrical circuit 19 (Fig. 9) which also includes a suitable source of current 20, which may be, for example, a battery of dry cells or the like arranged in the cabinet 11. Likewise arranged in this circuit 19 is an electromagnet 21 and when a ball enters one of the pockets 13 it closes the corresponding switch 18 and drops through the corresponding ball exit opening 15 in the slidable ball-retaining member 14, whence it will fall into

an inclined ball-return runway 95. In this manner, that is, by the closing of one of the switches 18, the electromagnet 21 is energized, whereupon it attracts its movable element 22, thereby pivoting the latter at 23 (clockwise, Fig. 3). This member 22 has an arm 24 which is pivotally connected, at 25, to a pawl 26 and this pawl 26 is, in turn, engageable with a ratchet 27 which is fixed on a horizontal shaft 28, this shaft 28 being rotatably mounted in an upright supporting frame 29 which is arranged in the cabinet 11. Arranged on the shaft 28 is a resetting coil spring 70 (Fig. 4).

Likewise mounted on and fixed to the horizontal shaft 28 is a printing or recording drum 30 and engageable with this printing drum 30 are spaced upper and lower inking rolls 31 and 32 (Fig. 4).

Engageable with the ratchet 27, to prevent retractive movement of the same, is an arm 33 of a latch dog 34, this latch dog 34 being pivotally mounted, at 35, and having an arm 36 which is attractable by an electromagnet 37 which is arranged in an auxiliary circuit 89 (Fig. 9), which 25 is associated with the principal circuit 19.

Arranged in the cabinet 11 is a web 38 of imprint-receiving material, such as paper, or the like, and this web 38 is advanced relative to and past the printing drum 30 by means of a web-advancing roll 39 which is rotatably mounted in the cabinet 11, for movement in a horizontal plane, upon a vertically extending shaft 41 (Fig. 4). Provided on the periphery of the web-advancing roll 39 are lugs 40 and these lugs 40 are engageable in corresponding openings which are formed in the web 38.

Mounted on the shaft 41, to which the web-advancing roller 39 is fixed, is a ratchet 42 and engageable with this ratchet 42 is a pawl 43 which is pivotally mounted upon a rocker arm 44, and this rocker arm 44 "floats", that is, is loosely mounted upon the shaft 41 (Figs. 7 and 8). Engageable with the ratchet 42, to prevent retrograde movement of the same, is a latch dog 45. Carried by the rocker arm 44 is a roller 46 (Figs. 1 and 7) and engageable with this roller 46 is an end portion 47 of an elongated bar 47 which is pivotally mounted between its ends, as at 48 (Fig. 1), in the cabinet 11. Pivotally connected to this bar 47, at one end of the same, as at 49 (Fig. 1), is a link 50 and this link 50 is pivotally connected at its other end, as at 51, to a coin slide 52 which is slidably mounted in an end wall 53 of the cabinet 11.

Pivotally connected to the rocker arm 44, as at 54 (Fig. 7), is an arm 55 and this arm 55 is pivotally connected, at one end, as at 56, to an arm 57 which is pivotally mounted on a vertical shaft 58 (Figs. 1 and 7). Likewise pivotally mounted on the shaft 58, that is, floating thereon, is an operating member 59 which has a laterally projecting arm 60 and this arm 60 of the member 59 is engageable with the web-severing and impression-transmitting device or member 61 which is pivotally mounted in the cabinet 11, as at 62, this urging and web-severing device 61 including a knife edge 87 and a resilient or pressure member 86 (Fig. 6). Mounted in the cabinet 11 upon the supporting wall 69 is a stationary knife edge 98 which cooperates with the knife edge 87 to form a shear.

The rocker arm 44 is normally urged in a counterclockwise direction (Fig. 7) by a spring 63 which has one end attached, as at 64, to the 75 rocker arm 44, the other end of this spring 63

being attached to the pivotal connection 56 between the link 55 and the arm 57 (Fig. 7). The operating member 59 and the web-severing and pressure member 61 are normally urged (in a clockwise direction, Figs. 7 and 6, respectively), by a spring 97 which has one end portion thereof attached to the member 61 (Fig. 6), the other end of the spring 97 being anchored in the cabinet 11, movement of the member 59, under the action of the spring 97 (clockwise, Fig. 7) being limited by a stop 65 with which the member 59 is engageable, this stop 65 being formed on a stationary upright member 94 which is arranged in the cabinet 11. Formed on this member 94 is a cam edge 92 (Fig. 7) and adapted to ride this cam edge 92 is a pawl 66 which is pivotally mounted on the arm 57. This pawl 66 is urged by a spring 100 into engagement with a notch 67 which is provided in the peripheral edge of the member 59 (Fig. 7).

The web 38 is fed through a guide slot 68 which is formed in an upright wall 69 of the supporting frame 96 (Fig. 6) and the web-severing and pressure member 61 is normally urged away from, or out of engagement with, the web 38 by means of the spring 97 (Fig. 6).

Attached to and depending from the slidable ball-retaining member 14 (Fig. 10) is an arm 71, and mounted on a vertical support 75 which is arranged in the cabinet 11, below the ball-retaining member 14, is a switch 74 which includes a relatively movable member 72 and a relatively stationary member 73.

Pivotally mounted on the support 75 (Fig. 10) adjacent the switch 74 is a switch-operating member 76 and this switch-operating member 76 includes a central portion 77, and a laterally extending arm 99, which arm 99 is adapted to be engaged by the depending arm 71 of the ball-retaining member 14. The switch-operating member 76 likewise includes an arm 78, to which is attached a spring 79, and this spring 79 normally urges the switch-operating member 76 into its initial position, as in Fig. 10, and in which position the central portion 77 thereof engages with the movable element or contact 72 of the switch 74; the relative rigidity or strength of the movable switch element or contact 72 being sufficient to offset or counteract the tendency of the spring 79 to move the resilient switch element or contact 72 into engagement with the stationary switch element or contact 73.

Slidably mounted in the end wall 53 of the cabinet 11 (Fig. 6) is a main and non-coin-operated control member or plunger 80 which is normally urged outwardly into its initial position (right to left, Fig. 6) by a resetting spring 81, this plunger 80 having an inner end portion 82 which is engageable with the web-severing and pressure member 61.

Provided in the cabinet 11 is a delivery chute 83 (Fig. 6) and this chute 83 opens at its lower end, exteriorly of the cabinet 11, through an outlet or delivery tray 84 which is formed in the end wall 53 of the cabinet 11.

Pivotally mounted as at 101 in the cabinet is a dash pot 85 (Fig. 1) and this dash pot 85 includes a movable element or piston rod 106 which is pivotally connected, as at 107, to the member 55, for a reason to be explained hereinafter.

Operation

When a ball, gravitating over the inclined playing board 12, enters into one of the ball-receiving pockets 13, it falls upon the correspond-

ing flexible switch element or contact 16 therein and bends the latter downwardly (from full to dotted line position, Fig. 2), thus causing the said flexible element or contact 16 to engage 5 the corresponding stationary switch element or contact 17 and thus close the corresponding switch 18, and the circuit 19.

When the circuit 19 is thus closed it energizes the electromagnet 21, whereupon the latter attracts its movable element or armature 22, thereby pivoting the latter, at 23 (clockwise, Fig. 3), against the action of its resetting spring 85, and this movement of the member 22 pivots the arm 24 thereof, at 25, relative to the pawl 26, thereby 10 moving the pawl 26 into engagement with the ratchet 27 and thus moving the ratchet 27, shaft 28, and the printing drum 30 a circumferential distance (counterclockwise, Fig. 3) equal to the circumferential distance between two of 15 the teeth on the ratchet 27. In this manner the printing drum 30 is advanced, relative to the web 38, by the action of the played balls entering the ball-receiving pockets 13 in the inclined playing board 12.

25 After completing this printing drum-advancing operation, the spent ball will roll off the resilient and flexible contact 16 into the ball return runway 95 for return to the elevating means (not shown).

30 When the printing drum 30 is thus advanced, in a circumferential step by step movement, relative to the web 38, the spring 70 is tensioned so that it may reset the printing drum in a manner to be explained presently. After the player 35 has completed playing a game upon the game apparatus which embodies the present invention, he may cause a ticket, having the score of his game printed thereon, to be dispensed from the cabinet 11, through the delivery outlet 84, by 40 pushing in on the main control member or plunger 80. When the main control member or plunger 80 is pushed in (left to right, Fig. 6) the inner end of the same engages the web-severing and pressure member 61 and thereby pivots the latter at 62 (counterclockwise, Fig. 6). During 45 this operation the resilient or pressure arm 86 of the member 61 engages the free end portion of the web 38 and forces the same into printing engagement with the peripheral surface of the printing drum 30, which surface may be provided by a rubber band arranged upon the drum 30, this printing surface being inked by the inking rollers 31 and 32. When the free end portion of 50 the web 38 is thus forced into printing engagement with the printing surface of the drum 30 the knife edge 87 (Fig. 6) of the member 61 engages the free end portion of the web 38 and coacts with the member 98 to sever the printed free end portion of the web 38 from the body of 55 the same, whereupon the plunger 80 may be released so that the thus printed and severed free end portion of the web 38 will drop onto the delivery chute 83, whence it will fall, by gravity, 60 into the delivery outlet or tray 84 and from 65 which it may be picked up by the player.

In the use of the present invention the resetting of the printing drum 30 back into its initial position is effected by operation of the slidable ball-retaining member 14, which is moved (left 70 to right, Fig. 2), by the action of the coin slide 52 when the latter is pushed in, the inner end portion of the coin slide engaging the depending arm 88 of the ball-retaining member 14.

When the slidable ball-retaining member 14 is 75 thus pushed in (left to right, Figs. 2 and 10)

the depending arm 71 thereof (Fig. 10) engages the laterally extending arm 99 of the switch operating member 76 and thereby pivots the latter (counterclockwise, Fig. 10) against the action of its resetting spring 79, and during this operation the depending arm 71 passes or moves by the lateral arm 99 of the switch-operating member 76. However, when the ball-retaining member 14 is returned to its initial position, (right to left, Fig. 10), (by a resetting spring not shown) 10 the depending arm 71 thereof engages the lateral arm 99 of the switch operating member 76 and thereby pivots the switch-operating member 76 (clockwise, Fig. 10), thus moving the central portion 77 of the switch-operating member 76 15 into engagement with the movable element or contact 72 of the switch 14, and thereby forcing the resilient switch element or contact 72 into engagement with the stationary switch element or contact 73 and thus closing the switch 14, after 20 which the depending arm 71 passes or moves by the lateral arm 99 so that the member 76 is free to move back into normal position (Figs. 2 and 10) by action of the movable element 72 of the switch 14.

When the switch 14 is thus closed, it closes the auxiliary circuit 89 (Fig. 9) to the electromagnet 37, and thereby energizes the electromagnet 37, and when the electromagnet 37 is thus energized it attracts the arm 36 of the latch dog 34 and 30 thereby pivots the latter, at 35 (clockwise, Fig. 3), against the action of its resetting spring 90, thus moving the arm 33 of the latch dog 34 out of latching engagement with the teeth of the ratchet 27, whereupon the tensioned resetting spring 70, on the shaft 28 (Fig. 4) will return the printing drum 30 back into its initial or zero position, it being understood that the lapse of time required for the depending arm 71 to pass the laterally extending arm 99 is sufficient to allow 40 the foregoing resetting operation to take place, and that when the switch 14 is returned to normal position the tensioned resetting spring 90 (Fig. 3) will then urge the arm 33 of the latch dog 34 back into latching engagement with the 45 teeth of the ratchet 27 so as to prevent retroactive or retrograde movement of the latter. It will thus be noted that the printing drum 30 is reset back into its initial position upon the return stroke of the ball-retaining member 14 (by the 50 closing of the switch 14), and the reason why this resetting operation takes place at this time will be made apparent presently.

When the coin slide 52 is pushed in (left to right, Fig. 1) it also moves the link 50 and this 55 link 50 acts upon the arm 47 to pivot the latter at 48 (clockwise, Fig. 1) and during this operation the end portion 91 of the member 47 engages the roller 46 and thereby pivots the rocker arm 44, upon the shaft 41 (clockwise, Figs. 1 and 7). During this operation the pawl 43, which is carried by the rocker arm 44, rides over the ratchet 42 (clockwise, Fig. 7). This movement of the rocker arm 44 (clockwise, Figs. 1 and 7) moves the link 55 (from full to dotted line position, Fig. 7), and this movement of the link 55, in turn, pivots the arm 57 (from full to dotted line position, Fig. 7). During this movement of the arm 57 the pawl 66, engaging in the notched portion 67 of the operating member 59, 70 pivots or rocks the member 59, on the shaft 58 (counterclockwise, from full to dotted line position, Fig. 7). During this operation the laterally extending arm 60 of the member 59 engages the member 61 and thereby pivots the latter, at 75

62 (counterclockwise, Fig. 6), thus causing the resilient portion or arm 86 of the member 61 to engage the free end portion of the web 38 in the event it has not been removed by the plunger 80 and thereby force the same into printing engagement with the printing drum 30, whereupon the cutting portion or knife edge 87 of the member 61 engages the free end portion of the web 38 and coacts with the knife edge 98 to sever 10 the thus printed free end portion of the web 38 from the body of the same, whereupon, the thus printed and severed free end portion of the web 38 will drop by gravity into the delivery chute 83 and will thence fall into the delivery outlet 84. 15 As the operating member 59 is pivoted (counterclockwise, from full to dotted line position, Fig. 7) the pawl 66 rides onto and over the cam edge 92 of the member 94, and after the laterally extending arm 60 has been forced into engagement with the web-severing and printing member 61 the pawl 66 is pivoted, by the lower end portion of the cam edge 92 (left hand end as seen in Fig. 7) (clockwise, Fig. 7) out of engagement with the notched portion 67 of the member 59, whereupon the tensioned resetting spring 97, will pivot the member 61 back into its initial position (as in Fig. 6). During this 25 operation the member 61 engages or bears against the laterally extending arm 60 of the operating member 59 and thereby pivots or rocks the latter about the shaft 58, back into its initial position (clockwise, from dotted to full line position, Fig. 7), and at the end of this movement the pawl 66 and the arm 57 are still in dotted 30 line position, Fig. 7, and are retarded in their return to initial position in a manner to be described presently.

In this manner the free end portion of the web 38 is printed, and the printed portion thereof is severed from the body of the same, by operation of the coin slide 52, so that in the event that a player who has made a relatively low score, or for any other reason fails to operate the main control member or plunger 80 40 and print his score upon the free end portion of the web 38, and sever the same from the body of the web 38, this ticket printing and web-severing operation will, nevertheless, be performed when the next succeeding player moves the coin slide 52 into full stroke position and it will be noted, in this connection, that this auxiliary ticket-printing and web-severing operation takes place slightly prior to the time that the web-advancing operation (which will 45 be described presently), takes place, as will now be explained, so that a clean, that is, unprinted, portion of the web 38 will be presented to the printing surface of the printing drum 30 to have imprinted thereon the score of the next 50 succeeding game played upon the apparatus with which the present invention is associated.

When the coin slide 52 is released and is returned to its initial position (by a resetting spring not shown) the member 47-91 is returned to its initial position (as in Figs. 1 and 7) whereupon the tensioned spring 63 acts upon the rocker arm 44 to pivot the same and the pawl 43 carried thereby, upon the shaft 41 (counterclockwise, from dotted to full line position, Fig. 7), and during this movement of the rocker arm 44 and pawl 43 the latter engages the ratchet 42 and thereby rotates the ratchet 42, shaft 41, and the web-advancing roll 39, which is mounted upon the shaft 41, a circumferential 75 distance equal to the circumferential distance

between two of the teeth on the ratchet 42. This movement of the web-advancing roll 39 advances the free end portion of the web 38 through the guide slot 68 (Fig. 6) and relative to and past the printing drum 30, and between the latter and the pressure and web-severing member 61-86-87.

Upon the return of the rocker arm 44 to initial position the arms 55 and 57 are likewise returned to initial position (dotted to full line, 10 Fig. 7) by the action of the tensioned spring 63. However, it is to be noted that the movement of the rocker arm 44 and arms 55 and 57 toward their initial position is retarded by the pivotal connection 107 of the piston rod 106 15 of the dash pot 85 to the arm 55, thereby assuring a gradual movement of the web 38 along its path through the guide slot 68 into impression-receiving position, that is, into a position between the web severing and printing member 20 61 and the printing drum 30.

It will thus be seen that if, for any reason, the player does not operate the main control member or plunger 80 to perform the web-printing and severing operations, at the end of a 25 game, these printing and web-severing operations will nevertheless be performed by the auxiliary control device 52-50-47-91-46-44-55-57-66-67-59 for the printing and web-severing or urging device 61-86-87 when the coin 30 slide 52 is again operated, that is, on the inward stroke of the coin slide 52 (left to right, Figs. 1 and 2), and it will further be noted, in this connection, that the auxiliary control device 52-50-47-91-46-44-55-57-66-67-59 for 35 the printing and web-severing, or urging, device 61-86-87 being thus operated on the inward stroke of the coin slide 52 (left to right, Figs. 1 and 2), causes the printing and web-severing device 61-86-87 to perform the print- 40 ing and web-severing operations prior to the time that the printing drum 30 is reset back into its initial position by its resetting spring 70, since this operation of resetting the printing drum 30 takes place on the return move- 45 ment of the ball-retaining member 14 (and coin slide 52), when the depending arm 71 of the ball-retaining member 14 engages the lateral arm 99 of the switch-operating member 76 to close the control switch 74 (Fig. 10) for the 50 electromagnet 37. It is thus assured that the web-severing and printing operations will always take place, through the operation of the auxiliary and coin-operated control device 52- 51-50-49-47-91-46-44-54-55-57-66- 55-67-59-60, for the printing and web-severing device 61-86-87 even though the player fails to, or neglects to, operate the main and non-coin-operated control device 80-82 for the printing and web-severing device 61-86-87 at the 60 end of a game.

While I have illustrated and described the preferred form of construction for carrying my invention into effect, this is capable of variation and modification, without departing from the 65 spirit of the invention. I, therefore, do not wish to be limited to the precise details of construction set forth, but desire to avail myself of such variations and modifications as come within the 70 scope of the appended claim.

Having thus described my invention, what I claim as new and desire to protect by Letters Patent is:

The combination with a game apparatus comprising a reciprocable coin slide and a switch 75

closable by a game playing member, of a score printing drum, means tending to return said drum to a given position, means controlled by said switch for actuating said drum to a score printing position upon closure of said switch by a playing member, means for retaining said drum in said position against the action of said returning means, means for feeding the web section into printing position with respect to said drum, web severing means, means actuatable by said coin slide during a stroke thereof in one

direction for effecting the printing of a score upon said web section and severing the same, and means operable by said slide during a stroke thereof in the opposite direction for effecting the operation of said web feeding means for feeding a succeeding section of the web into printing position and effecting the release of said drum by said retaining means for restoration of the same to initial position by said drum return means.

5
